FERDINAND Q. HARTMAN AND EUGENE ATWOOD HARTMAN, OF DANVILLE, PENNSYLVANIA.

THREAD-BREAKING DEVICE FOR SPINNING MACHINES.

Application filed January 23, 1925. Serial No. 4,251.

To all whom it may concern:

Be it known that we, FERDINAND Q. HARTMAN and EUGENE ATWOOD HARTMAN, citizens of the United States, and residents of 5 Danville, in the county of Montour and State of Pennsylvania, have invented a new and useful Improvement in Thread-Breaking Devices for Spinning Machines, of which the following is a specification.

10 Our invention relates to a thread breaking device for spinning machines and more particularly to a thread breaking device which may be applied to spinners for independently spinning a plurality of threads 15 and winding the threads so spun on a single spool, from which spool the threads are subsequently to be twisted into one strand on a twisting machine. It is very essential in spinning a plurality of threads at the same 20 time and winding them together on a spool or bobbin, that a single thread or a less number than the whole number of threads being spun, be not allowed to run onto the spool as this would produce a serious defect when the 25 threads so spun are finally twisted into a strand.

Our present invention is directed to a thread breaking device which may be interposed between the spindles and the take up 30 spool upon which the spun threads are wound, and which shall be under the control of thread supporting devices carried by the breaker, to perform the function of breaking a companion thread when another 35 thread is unintentionally parted, so that the several threads may be united before any one or more of the threads has or have been allowed to be wound upon the take up spool without its or their companion thread or 40 threads.

The object of our invention is to provide a device of this character which is efficient, positive in operation, simple in construction, and inexpensive to manufacture.

45 Another object consists in providing a device which has a thread guiding bar mounted to oscillate on the thread breaker, which is located in position to be thrown off center by the rocking movement of the bar, 50 which movement is actuated by the breaking of a thread.

Another object is to provide a device having a horizontally disposed bar rotatably mounted in the device for supporting the

threads and relieving the bar of certain frictional contact as the thread passes thereover. 55

Another object is to provide a structure having guide arms vertically disposed to spread or separate the threads laterally on the supporting bar of the thread breaker. 60

Another object is to provide novel means of mounting the device on the thread breaker so that the device may be limited in its oscillatory movement thereon.

Another object consists in providing certain improvements in the form, construction and arrangement of the several parts whereby the above named and other objects may be effectively attained. 65

A practical embodiment of our invention 70 is represented in the accompanying drawings, in which

Fig. 1 represents a front elevation of the device in operative position so much of a spinning machine being shown as will suffice to disclose a practical application of our 75 invention.

Fig. 2 represents a vertical section taken in the plane of the line II—II of Fig. 1, looking in the direction of the arrows. 80

Fig. 3 represents a detail horizontal section taken in the plane of the line III—III of Fig. 2, looking in the direction of the arrows. 85

Fig. 4 represents a front elevation of a modified form of spreader for the threads.

Fig. 5 represents a side elevation of the same.

Fig. 6 represents a detail plan view on a larger scale of the device for supporting the threads together with the means by which it is mounted on the thread breaker. 90

Fig. 7 represents a vertical section taken in the plane of the line VII—VII of Fig. 6, looking in the direction of the arrows, and 95

Fig. 8 represents a vertical section taken in the plane of the line VIII—VIII of Fig. 6, looking in the direction of the arrows.

In the form shown in Figs. 1 to 3 inclusive, the main frame of the machine at one end is denoted by 1, the take up spool by 2, the traverse guide for assembling the threads and laying them on the take up spool, by 3, the wheel for driving the take up spool by 4, and a pair of spindles for spinning two independent threads by 5, 6. 100

The bobbins which carry the threads are mounted on the spindles 5 and 6 in the usual 105

2 manner and are indicated by 7 and 8. The threads which lead from the respective bobbins 7, 8 are denoted by 9 and 10. For the purpose of supporting the thread breaker 5 mechanism in proper position on the spinning machine so that there shall be one for each group of threads to be combined on a single take up spool, we secure a horizontal rail 11 to the end frame of the spinning 10 machine. This rail may be composed of wood so as to receive screws 12 for attaching the brackets 13 of the thread breaking mechanism in position. Each bracket 13 is provided with a frame 14 having depending 15 lugs 15, 16 arranged to receive a pintle 17 upon which is mounted a thread breaker 18. The thread breaker 18 comprises a downwardly extending arm 19 having a cross head 20 which terminates in hook eyes 21, 22, and an upwardly extending arm 23 which is so weighted as to overbalance the downwardly extending arm 19. Upon the upper end of the arm 23 there is mounted a thread guiding device, which comprises, in 25 the present instance, a rectangular block 24 having a horizontally disposed bar 25 mounted to rotate therein. This bar 25 extends in opposite directions from the block 24 and is maintained in this position by 30 means of wire collars 26, 27 secured thereto. The block is secured in position to oscillate on the arm 23 by means of a U-shaped element 28 having a member 29 arranged to pass through an opening 30 in the block 24 35 and to be seated in a recess 31 in the arm 23. The other member 32 of the element 28 extends downwardly and is provided with a laterally turned end 33 which enters a hole 34 in the arm 23. The members 29 and 32 of the element 28 are arranged to 40 yield so that the end 33 will be normally held in the hole 34.

A pair of guide arms 35, 36 are disposed in the frame 14 and extend upwardly and 45 outwardly in front of the rotatable bar 25 so as to hold the threads in position upon opposite sides of the block 24 as they pass over and from the bar 25.

A guide eye 37 is secured to a support 50 fixed to the frame 14, by means of a screw 39, which guide eye 37 tends to assemble the threads in their passage upwardly and over the traverse bar 3 to the take up spool 2.

In the modified form shown in Figs. 4 55 and 5, the guide arms 40 and 41 are disposed in a frame 42 and extend upwardly and outwardly therefrom. Each of the guide arms 40, 41 is provided with a guide eye or pigtail 43 arranged in opposite relation and 60 serves to hold its thread in position on a rotatable guide bar 44 carried by a rectangular block 45, which is mounted to oscillate on a U-shaped element 46 secured to the upwardly extending arm 47 of the thread 65 breaker 48.

While we have specifically described the block and its adjacent parts as shown in Figs. 1, 2, 3, 6, 7 and 8, we wish to particularly point out the fact that the breaker 48 with its rectangular block 45 and its adjacent parts as shown in the modified form in Figs. 4 and 5 are identical in structure and operation.

In operation of the structure shown in Figs. 1 to 3 inclusive, the threads which lead from the bobbins 7, 8 are directed upwardly upon opposite sides of the breaker 18, over the rotatable bar 25, thence outwardly and substantially at right angles thereto, thence partially around the guide arms 35, 36 inwardly to the guide eye 37, where they are associated and travel upwardly over the traverse bar 3 onto the take up spool 2. If, during the operation of the machine, one of the threads 9, 10 accidentally breaks, the 75 tension on one end of the rotatable bar 25 will be relieved and the drag of the unbroken thread on the opposite end of the bar 25 will cause the block 24 to rock or swing 80 arcuately on the member 29 of the element 28 to the position shown in dotted outline in Figs. 2 and 6. This arcuate movement in conjunction with the uneven tension on the opposite ends of the bar 25, will tend to 85 overbalance the breaker 18 and cause the upwardly extending arm 23 to move rearwardly by gravity and the downwardly extending arm 19 to swing forwardly to the position shown in dotted outline in Fig. 2. In this position the crosshead 20 with its 90 hook eyes 21, 22, will be brought into the path of the whirl of the unbroken thread, which will be caught by one of the hook eyes 21, 22, form a loop therein, which will 95 promptly break the unbroken thread. Thus the operator will be enabled to join the broken ends of each of the group of threads being wound upon the take up spool 2, so that there may be, at no time, any distance 100 of single thread wound on the take up spool and the defect which would otherwise take place in the finally twisted strand is thereby avoided.

In operation of the form shown in Figs. 4 and 5, each of the threads after passing 105 from the rotatable bar 44 on opposite sides of the block 45, is directed through the guide eye or pigtail 43, thence upwardly to be assembled at the traverse bar and spool (not shown).

It will be understood that various changes may be resorted to in the form, construction and arrangement of the several parts without departing from the spirit and scope of our invention; and hence, we do not intend to be limited to the details herein shown and described, except as they may be included in the claims.

What we claim is:

1. A device of the character described 130

comprising, a counterbalance thread breaker pivoted to swing into position to break the threads, and a device mounted to oscillate on said breaker and provided with a bar for supporting the threads, whereby the breaking of a thread will free the bar and cause the device to rock and the breaker to swing into the path of the unbroken thread.

2. A device of the character described comprising, a counterbalance thread breaker pivoted to swing into position to break the threads, and a device mounted to oscillate on said breaker and provided with a bar extending in opposite directions therefrom for supporting the threads, whereby the breaking of a thread will free one end of the bar and cause the device to rock and the breaker to swing into the path of the unbroken thread.

3. A device of the character described comprising, a counterbalance thread breaker pivoted to swing into position to break the threads, and a device mounted to oscillate on said breaker and provided with a bar rotatably journaled therein for supporting the threads, whereby the breaking of a thread will free the bar and cause the device to rock and the breaker to swing into the path of the unbroken thread.

4. A device of the character described comprising, a counterbalance thread breaker pivoted to swing into position to break the threads, and a device mounted to oscillate on said breaker and provided with a bar extending in opposite directions therefrom and rotatably journaled therein for supporting the threads, whereby the breaking of a thread will free one end of the bar and cause the device to rock and the breaker to swing into the path of the unbroken thread.

5. A device of the character described comprising, a frame, a counterbalance thread breaker pivoted therein and adapted to swing into position to break the threads, guides carried by the frame having eyes for separating the threads, and a device mounted to oscillate on said breaker and provided with a bar coacting with said guides to support the threads, whereby the breaking of a thread will free the bar and cause the device to rock and the breaker to swing into the path of the unbroken thread.

6. A device of the character described comprising, a frame, a counterbalance thread breaker pivoted therein and adapted to swing into position to break the threads, guides carried by the frame for separating the threads, and a device mounted to oscillate on said breaker and provided with a bar extending in opposite directions therefrom and arranged to coact with said guides to support the threads, whereby the breaking of a thread will free one end of the bar and cause the device to rock and the breaker to swing into the path of the unbroken thread.

7. A device of the character described comprising, a frame, a counterbalance thread breaker pivoted therein and adapted to swing into position to break the threads, guides carried by the frame for separating the threads, and a device mounted to oscillate on said breaker and provided with a bar rotatably journaled therein and arranged to coact with said guides for supporting the threads, whereby the breaking of a thread will free the bar and cause the device to rock and the breaker to swing into the path of the unbroken thread.

8. A device of the character described comprising, a frame, a counterbalance thread breaker pivoted therein and adapted to swing into position to break the threads, guides carried by the frame for separating the threads, and a device mounted to oscillate on said breaker and provided with a bar extending in opposite directions therefrom and rotatably journaled therein, said bar being arranged to coact with said guides for supporting the threads, whereby the breaking of a thread will free one end of the bar and cause the device to rock and the breaker to swing into the path of the unbroken thread.

9. A device of the character described comprising, a counterbalance thread breaker pivoted to swing into position to break the threads, and a device carried by said breaker, said device comprising a block, a bar located therein for supporting the threads, and means for pivotally mounting said block on the breaker, whereby the breaking of a thread will free the bar and cause the device to rock and the breaker to swing into the path of the unbroken thread.

10. A device of the character described comprising, a counterbalance thread breaker pivoted to swing into position to break the threads, and a device carried by said breaker, said device comprising a block, a bar extending in opposite directions therefrom for supporting the threads, and means for pivotally mounting said block on the breaker, whereby the breaking of a thread will free the bar and cause the device to rock and the breaker to swing into the path of the unbroken thread.

11. A device of the character described comprising, a counterbalance thread breaker pivoted to swing into position to break the threads, and a device carried by said breaker, said device comprising a block, a bar rotatably journaled therein for supporting the threads, and means for pivotally mounting said block on the breaker, whereby the breaking of a thread will free the bar and cause the device to rock and throw the breaker off center into the path of the unbroken thread.

12. A device of the character described comprising, a counterbalance thread break-

er pivoted to swing into position to break the threads, and a device carried by said breaker, said device comprising a block, a bar located therein for supporting the threads, and means for pivotally mounting said block on the breaker, said means including an element having a pivot for the block and a member for securing the block to the breaker, whereby the breaking of a thread will free the bar and cause the device to rock and throw the breaker off center into the path of the unbroken thread.

13. A device of the character described comprising, a counterbalance thread breaker pivoted to swing into position to break the threads, and a device carried by said breaker, said device comprising a block, a bar extending in opposite directions therefrom and rotatably journaled therein for supporting the threads, and means for pivotally mounting said block on the breaker, said means including an element having a pivot for the block and a member for securing the block to the breaker, whereby the breaking of a thread will free the bar and cause the device to rock and throw the breaker off center into the path of the unbroken thread.

14. A device of the character described comprising, a counterbalance thread breaker pivoted to swing into position to break the threads, and a device carried by said

breaker, said device comprising a block, a bar located therein for supporting the threads, and means for pivotally mounting said block on the breaker, said means including an element having a pivot member for the block and a resilient member for securing the block to the breaker, whereby the breaking of a thread will free the bar and cause the device to rock and throw the breaker off center into the path of the unbroken thread.

15. A device of the character described comprising, a counterbalance thread breaker pivoted to swing into position to break the threads, and a device carried by said breaker, said device comprising a block, a bar extending in opposite directions therefrom and rotatably journaled therein for supporting the threads, and means for pivotally mounting said block on the breaker, said means including an element having a pivot member for the block and a resilient member for securing the block to the breaker, whereby the breaking of a thread will free the bar and cause the device to rock and throw the breaker off center into the path of the unbroken thread.

In testimony, that we claim the foregoing as our joint invention, we have signed our names this 15th day of January, 1925.

FERDINAND Q. HARTMAN.
EUGENE ATWOOD HARTMAN.
